UNITED STATES PATENT OFFICE.

LOUIS A. MORTIMER OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

Application filed December 29, 1919. Serial No. 347,881.

To all whom it may concern:

Be it known that I, LOUIS A. MORTIMER, a citizen of the United States, residing at New York, in the county of New York, 5 State of New York, have invented certain new and useful Improvements in Telephone Systems, of which the following is a full, clear, concise, and exact description.

This invention relates to an improved 10 method and means for signaling over transmission lines and has particular reference to such method and means as applied to telephone systems.

In systems of this nature, it has been proposed to employ physical and phantom lines 15 for interconnection between distant offices. It has also been proposed to employ these lines for the transmission of current impulses of various natures to signal operators 20 at the distant offices and to control the operation of repeater apparatus at intermediate offices.

An object of the invention is to render effective a plurality of repeaters by transmitting 25 an impulse over any one of a number of transmission lines with which the repeaters are associated and disabling said repeaters by an impulse transmitted over only one of said lines.

30 The above and other objects will be apparent from the following description taken in connection with the accompanying drawings, wherein Figs. 1 to 4 inclusive, taken together and arranged side-by-side in the manner indicated by the circuit lines extending to the margins of the drawings, illustrate a preferred embodiment of the invention and Fig. 5 is a diagrammatic view of one of the cord circuits employed in connection with 35 the invention.

The invention is shown as consisting of 40 physical lines A and C and a phantom line B interconnecting two distant offices W and Z and two intermediate offices or stations X and Y. A signaling circuit is simplex 45 with windings of repeating coils of line A and is utilized for the purpose of transmit-

ting signaling impulses upon the initiation or termination of a call on either of the lines A or B. Such impulses also render 50 effective the telephone repeaters RA1 and RC1 associated with lines A and C at office X and RA2 and RC2 associated with said lines at office Y. Another signaling circuit is likewise simplex with windings of repeating coils of line C, and impulses are transmitted over said circuit for signaling the operator at a distant office or for disabling the battery supply for the filaments 55 of telephone repeaters RA1 and RC1 associated with said lines A and C at office X, and RA2 and RC2 associated with said lines at office Y when all the lines become idle. The telephone repeaters are not shown in detail since they may be of any usual type 60 such as those employing vacuum tubes. Polarized relays 5 and 6 at office X are placed in series, respectively, with the signaling 65 circuits associated with lines A and C, and the operation of either of said relays, in response to a signaling or selective impulse 70 transmitted for any one of the lines, controls a common relay 7, whereby battery supply is connected to the filaments of the repeaters at said office to render the same 75 effective. The repeaters RA2 and RC2 at office Y are controlled by a common relay 80 which is responsive to the energization of polarized relays 81 and 91 on calls initiated at office W, and polarized relays 86 and 96 on calls initiated at office Z. Relays 81 and 86 are arranged in the signaling circuit associated with the physical line A, and also control the signal repeating relays 82, 83, 84 and 85, while relays 91 and 96 are in 85 series with the signaling circuit connected to physical line C, and in a similar manner control signal repeating relays 92, 93, 94 and 95. The circuit arrangement at office Z is similar in all respects to that at office W, 90 whereby signals may be received and transmitted therefrom in the same manner as at office W. The signaling circuits also include polar relays 34 and 74 at office W and simi-

lar relays 134 and 174 at office Z selectively responsive in each case to the impulses transmitted from the other office. It is believed that the invention will now be fully understood from the following detailed description of the operation.

Operator at office W initiates a call over line A.

- 10 The operator at office X desiring to extend a call to the office Z, or desiring to communicate with the operator at the latter office, inserts plug 13 of a link circuit D at office W into jack 20 of line A, relays 14 and 21 operating over a circuit extending from battery through the winding of relay 14 of the selected link circuit, the sleeve contacts of plug 13 and jack 20 and the winding of relay 21 to ground. Relay 30 thereupon operates over a circuit extending from battery through the winding of relay 30, the right-hand normal contact of relay 29, the left-hand normal contact of relay 28 and the right-hand alternate contact of relay 21 to ground. Relay 29 thereupon operates over a circuit extending from battery through the alternate contact of relay 30, winding of relay 29 and the right-hand normal contact of relay 50 to ground. The operation of relay 29 releases relay 30, but since relay 29 is slow to release, relay 28 operates over a circuit extending from battery through the left-hand normal contact of relay 30, the right-hand alternate contact of relay 29, the middle normal contact of relay 28, winding of relay 28, the middle normal contact of relay 30, and the right-hand alternate contact of relay 21 to ground. Relay 28 locks over a circuit extending from battery through the right-hand alternate contact and winding of relay 28, the middle normal contact of relay 30, and the right-hand alternate contact of relay 21 to ground. During the period that relay 29 is operated, a circuit is completed from the positive terminal of the 120 volt source of current, through the contact of relay 27, the left-hand alternate contact of relay 29, the upper bridged winding of relay 34, the simplex conductors of line A extending from office W to office X, the winding of relay 5, the simplex conductors of line A extending from office X to office Y, and the winding of relay 81 to ground, at the normal contact of relay 85. The direction of current flow in this circuit is such that relay 5 closes its right-hand contact and relay 81 closes its lower contact. In closing its right-hand contact relay 5 causes the operation of relay 7 over an obvious circuit and the closure of the right-hand and middle contacts of relay 7 completes the filament current supply circuits for repeaters RA1 and RC1, associate with line circuits A and C respectively. Relay 7 locks over a circuit extending from battery through the winding and left-hand contact of relay 7 and the contact of relay 8 to ground. Relay 81 in closing its lower contact causes the operation of relay 83 over an obvious circuit. The closure of the left-hand contact of relay 83 causes the operation of relay 90 over an obvious circuit and the closure of the middle and right-hand contacts of relay 90 in a similar manner completes the filament battery supply circuits for repeaters RA2 and RC2 associated with the lines A and C, respectively, at office Y. Relay 90 locks over a circuit extending from battery through the winding and left-hand contact of relay 99, the right-hand normal contact of relay 94, and the left-hand normal contact of relay 92 to ground. Relay 81 releases upon the cessation of the impulse being transmitted, but during the period that the lower contact thereof is closed, relay 83 in closing its right-hand alternate contact establishes a circuit extending from positive terminal of the 120 volt source of current through the right-hand alternate contact of relay 83, the normal contact of relay 82, the upper bridged winding around the relay 86, the simplex conductors of line circuit A extending from office Y to office Z and the winding of relay 134 to ground at the right-hand contact of relay 149. The direction of current flow in this circuit is such that relay 134 closes its lower contact, completing a circuit extending from battery through the winding of relay 126, the right-hand normal contact of relay 121 and the lower contact of relay 134 to ground. Lamp 123 is thereby lighted over an obvious circuit and relay 127 is operated over a circuit extending from battery through the winding of relay 127, left-hand alternate contact of relay 126, and the left-hand normal contact of relay 121 to ground. The operation of the relay 127 prevents the transmission of a signal from office Z to office W. After the transmission of the impulse, relays 28 and 21 at office W remain operated and relays 126 and 127 at office Z remain operated.
- 115 In response to the closure of the middle alternate contact of relay 21, relay 1 operates over an obvious circuit, causing the operation of slow-release relay 2 over an obvious circuit, thus removing the ground connection at relay 2 for the operating circuit of relay 74, and preparing a circuit for disabling the telephone repeaters.
- 120 *Operator at office Z answers the call received over line A.*
- 125 The operator at office Z observing the lighted condition of lamp 123, inserts plug 13 of a link circuit D at office Z into jack 120, causing the operation of relays 14 and 121

over a circuit extending from battery through the winding of relay 14, the sleeve contacts of plug 13 and jack 120 and the winding of relay 121 to ground. Relay 126 releases upon the operation of relay 121 and causes the extinguishment of lamp 123 and the release of relay 127. The operation of relay 121 also causes the operation of relay 130 over a circuit extending from grounded battery through the winding of relay 130, the left hand normal contact of relay 129, the right hand normal contact of relay 128, and the left hand alternate contact of relay 121 to ground. The operation of relay 130 closes an operating circuit for relay 129 extending from grounded battery through the right hand alternate contact of relay 130, the winding of relay 129 and the left hand normal contact of relay 150 to ground. Relay 129 thereupon locks over a circuit extending from battery through the left hand normal contact of relay 128, the middle alternate contact and winding of relay 129 and the left hand normal contact of relay 150 to ground. The opening of the left hand normal contact of relay 129, opens the circuit of and causes the release of relay 130, whereupon relay 128 operates over a circuit extending from battery through the right hand normal contact of relay 130, the left hand alternate contact of relay 129, the middle contact of relay 128 and the winding thereof, the middle contact of relay 130 and the left hand alternate contact of relay 121, to ground. The opening of the left hand normal contact of relay 128 causes the release of relay 129. However, during the period in which the relay 129 is operated, a circuit is completed extending from the positive terminal of the 120 volt source of current through the contact of relay 127, the right hand alternate contact of relay 129, the upper bridged winding around relay 134, the simplex conductors of line circuit A extending from office Z to office Y, winding of relay 86, the lower bridged winding around relay 86, and the normal contacts of relays 82 and 83 to ground. Relay 86, in response to the current flowing over such circuit, closes its lower contact, causing the operation of relay 85 over an obvious circuit. The closure of the right hand alternate contact of relay 85 produces no material effect upon the circuit since relay 90 has been previously locked in an operated condition. The closure of the left hand alternate contact of relay 85, however, completes a circuit during the continuation of the impulse which extends from the positive terminal of the 120 volt source of current through the left hand alternate contact of relay 85, left hand normal contact of relay 84, the upper bridged winding around relay 81, the simplex conductors of line circuit A extending from office Y to office X, the winding of relay 5, the simplex conductors of line circuit A extending from office X to office W, the winding of relay 34, the lower bridged winding around said relay, the left hand normal contact of relay 29 and the left hand normal contact of relay 49, to ground. Although relay 5 closes its right hand contact in response to the current flowing therethrough, no material effect is produced upon the system, since relay 7 remains locked over a circuit previously described. The direction of current flowing through the winding of relay 34 is such that the lower contact thereof is closed, causing the operation of relay 24 over a circuit extending from battery through the winding of relay 24, the left hand alternate contact of relay 21, and the lower contact of relay 34 to ground. The operation of relay 24 connects a source of ringing current to the line and link circuit which will give a momentary audible signal to the operator at office W, whose listening key 15 is actuated at this time to indicate that the operator at office Z has responded by inserting a plug into jack 120. The operator at office Z may converse with the operator at office W by the actuation of listening key 15 in the link circuit associated with line circuit A, which connects the operator's telephone set (not shown) to the associated link circuit in the usual manner.

Operator at office W initiates a call over line circuit B.

The operator at office W, desiring to contemporaneously extend a call over the line circuit B, inserts plug 13 of a selected link circuit D into jack 40 of line circuit B, thereby causing the operation of relays 14 and 41 over a circuit extending from battery through the winding of relay 14, the sleeve contacts of plug 13 and the jack 40, and winding of relay 41 to ground. Relay 50 operates over a circuit extending from battery through the winding of relay 50, right-hand normal contact of relay 49, the left-hand normal contact of relay 48 and the right-hand alternate contact of relay 41 to ground. Relay 49 thereupon operates over a circuit extending from battery through the alternate contact of relay 50, the winding of relay 49, and the right-hand normal contact of relay 30 to ground. Relay 49 locks over a circuit extending from battery through the right hand normal contact of relay 48, the middle alternate contact and winding of relay 49, and the right-hand normal contact of relay 30 to ground. The operation of relay 49 opens the circuit for relay 50 causing the release thereof which causes the operation of relay 48 over a circuit extending from battery through the left-hand normal contact of relay 50, the right-hand alternate contact of relay 49, the middle normal contact and winding of relay 48, the middle nor-

mal contact of relay 50 and the right-hand alternate contact of relay 41 to ground. Relay 48 locks over a circuit extending from battery through the right-hand alternate 5 contact and winding of relay 48, the middle normal contact of relay 50 and the right-hand alternate contact of relay 41 to ground. In operating, relay 48 releases relay 49. However, during the period that relay 49 re- 10 mains operated, a circuit is established from the negative terminal of the 120 volt source of current, through the contact of relay 47, the left-hand alternate contact of relay 49, the left-hand normal contact of relay 29, 15 the upper bridged winding around relay 34, the simplex conductors of line circuit A extending from office W to office X, the winding of relay 5, the simplex conductors of line circuit A extending from office X to of- 20 fice Y, and the winding of relay 81 to ground at the normal contact of relay 85. The direction of current flow in this circuit is such that relay 5 closes its left-hand contact and relay 81 closes its upper contact. The opera- 25 tion of relay 5 at this time has no effect upon the system since relay 7 is locked in an operative condition. The closure of the upper contact of relay 81, however, causes the operation of relay 82 over an obvious 30 circuit. The closure of the left-hand alternate contact of relay 82 produces no ma- terial effect upon the system since relay 90 35 has been previously operated and remains locked in an operated condition, but the closure of the right-hand contact of relay 82 completes a circuit from the negative terminal of the 120 volt source of current through the right-hand alternate contact of relay 82, the upper bridged winding around 40 relay 86, the simplex conductors of line circuit A extending from office Y to office Z and the winding of relay 134 to ground at the right-hand contact of relay 149. The direction of current flow through this circuit 45 during the period of transmission of the im- pulse, is such that relay 134 closes its upper contact thereby operating relay 146 over a circuit extending from battery through the winding of relay 146, right-hand normal 50 contact of relay 141, and the upper contact of relay 134 to ground. Relay 146 is locked over a circuit extending from battery through the winding and left-hand contact of relay 146 and the left-hand normal con- 55 tact of relay 141 to ground. Lamp 143 is lighted over an obvious circuit to signal the operator that a call is being extended over the phantom line circuit B. The closure of the left-hand contact of relay 146 operates 60 relay 147 over a circuit extending from bat- tery through the winding of relay 147, the left-hand contact of relay 146 and the left- hand normal contact of relay 141 to ground. After the impulse has been transmitted, re- 65 lays 41 and 48 at office W are in an operated

condition while relays 146 and 147 at office Z are in an operated condition.

Operator at office Z answers a call initiated over line B.

70

Observing the lighted condition of lamp 143 the operator at office Z inserts the plug 13 of a link circuit D thereat into the jack 140, thereby causing the operation of relays 14 and 141, over a circuit extending from 75 battery through the winding of relay 14 sleeve contacts of plug 13 and jack 140 and winding of relay 141 to ground. The opening of the left-hand normal contact of relay 141 releases relays 146 and 147, thereby ex- 80 tinguishing lamp 143. A signaling impulse to inform the operator at office W that the operator at office Z has answered the call is transmitted in the same manner as herein- 85 before set forth in connection with line A. The relay 44 is operated in this instance, as will more clearly appear in the following description of the transmission of a disconnect signal from office Z to office W. Upon 90 the actuation of listening key 15 in the link circuit D, associated with the line circuit B at office Z, the operator thereat may communicate with the operator at office W over the phantom line circuit B which is com- 95 posed of physical lines or side circuits A and C.

Operator at office W initiates a call over line Circuit C.

100

Desiring to contemporaneously extend another call from office W to office Z, the operator at office W inserts the plug 13 of a link circuit D thereat into jack 60 of the line circuit C, thereby operating relays 14 and 61 over a circuit extending from bat- 105 tery through the winding of relay 14, the sleeve contacts of plug 13 and jack 60, and the winding of relay 61 to ground. Relay 70 operates over a circuit extending from bat- 110 tery through the winding of relay 70, the right-hand normal contact of slow-releasing relay 69, the left-hand normal contact of relay 68 and the right-hand alternate contact of relay 61 to ground. Relay 69 there- 115 upon operates over a circuit extending from bat- tery through the alternate contact of relay 70 and the winding of relay 69 to ground. Relay 69 thereupon locks over a circuit extending from battery through the right-hand normal contact of relay 68, and the middle alternate contact and winding of relay 69 to ground. The opening of the right-hand normal contact of relay 69 causes the release of relay 70 so that relay 68 is operated over a circuit extending from bat- 120 tery through the left-hand normal contact of relay 70, the right-hand alternate contact of relay 69, the middle normal contact and winding of relay 68, the right-hand normal contact of relay 70, and the right- 125 130

hand alternate contact of relay 61 to ground. Relay 68 in operating locks over a circuit extending from battery through the right-hand alternate contact and winding of relay 68, the right-hand normal contact of relay 70, and the right-hand alternate contact of relay 61 to ground. Relay 69 is thereupon released due to the opening of the right-hand normal contact of relay 68.

10 However, during the period that relay 69 is in an operated condition a circuit is established from the positive terminal of the 120 volt source of current, through the contact of relay 67, the left-hand alternate contact of relay 69, the upper bridged winding around relay 74, the simplex conductors of line circuit C extending from office W to office X, the winding of relay 6, the simplex conductors of line circuit C extending from office X to office Y, and the winding of relay 91 to ground at the normal contact of relay 95. The direction of current flow in this circuit is such that relay 6 closes its left-hand contact and relay 91 closes its lower contact. The operation of relay 6 produces no material effect on the system since relay 7 is locked in an operative condition due to the previous calls which have been transmitted over line circuits A and B.

20 However, during the period that the impulse is being transmitted in connection with the call being extended over the line circuit C, relay 93 operates over an obvious circuit to complete a circuit for operating relay 90, but inasmuch as this relay is already locked, the operation of relay 93 has no effect thereon. Relay 93 also completes a circuit extending from the positive terminal of the 120 volt source of current through the right-hand alternate contact of relay 93, the right-hand normal contact of relay 92, the upper winding bridged around relay 96, the simplex conductors of line circuit C extending from office Y to office Z, the winding of relay 174 and the lower winding bridged therearound the right-hand normal contact of relay 169 and the left-hand alternate contact of relay 101 to ground. The direction of current flow through this circuit is such that relay 174 closes its lower contact thereby causing the operation of relay 166 over a circuit extending from battery through the winding of relay 166, the right-hand normal contact of relay 161 and the lower contact of relay 174 to ground. Lamp 163 is thereupon lighted over an obvious circuit and relay 167 is operated over a circuit extending from battery through the winding of relay 167, the left-hand alternate contact of relay 166 and the left-hand normal contact of relay 161 to ground. The operation of relay 167 prevents the transmission of a signaling impulse from office Z to office W. Relay 166 is locked over a circuit extending from battery through the winding and left-hand al-

ternate contact of relay 166 to the left-hand normal contact of relay 161 to ground, and relay 167 is also locked over a similar circuit. After the signaling impulse has been transmitted, relays 61 and 68 at office W remain in an operative condition while relays 166 and 167 at office Z remain in an operated condition.

15 *Operator at office Z answers a call being extended over line circuit C.*

The operator at office Z observing the lighted condition of lamp 163 inserts plug 13 of a link circuit D thereat into jack 160, thereby causing the operation of relays 14 and 161 over a circuit extending from battery through the winding of relay 14, sleeve contacts of plug 13 and jack 160 and the winding of relay 161 to ground. The opening of the left-hand normal contact of relay 161 causes the release of relays 166 and 167, thereby extinguishing lamp 163. A signaling impulse for operating relay 64 is now transmitted, in the same manner as previously described in connection with line A, to office W to inform the operator at said office that the call has been answered at office Z. By actuating listening key 15 of the selected link circuit D, the operator at office Z may communicate with the operator at office W.

20 *Operator at office Z transmits disconnect signal to the operator at office W over line circuit A.*

Upon the completion of the conversation over line circuit A, the operator at office Z may actuate ringing key 18 of the link circuit D, at office Z associated with the line circuit A, thereby operating relay 125 over a circuit from the source of alternating current through the lower alternate contact of ringing key 18, the ring contacts of plug 13 and jack 120, the lower normal contact of relay 124, the winding of the repeating coil, winding of relay 125, and the condenser 131 shunting the condenser 132, the upper normal contact of relay 124, the tip contacts of jack 120 and plug 13, and the upper alternate contact of ringing key 18 to ground. The closure of the left-hand contact of relay 125 short-circuits the winding of the repeating coil to thereby prevent the ringing current being induced into the outgoing section of the line circuit through such coil. The closure of the right-hand contact of relay 125 causes the operation of relay 130 over a circuit extending from battery through the winding of relay 130 the right-hand normal contact of relay 129, the right-hand alternate contact of relay 128 and the right-hand contact of relay 125 to ground. The locking circuit of relay 128 is opened at middle normal contact of relay 130. From this point to the energization of relay 24, the operation

of transmitting a signal to office W to light lamp 17 is the same as described in connection with the transmission of a signal to office W when the operator at office Z answered 5 the call on line A. Supervisory relay 16, in the link circuit D associated with the line circuit A, is thereupon operated over a circuit extending from the source of alternating current through the lower alternate contact of relay 24, the ring contacts of jack 20 and plug 13, the lower normal contact of key 18, the left-hand winding of relay 16, the condenser 19, the upper normal contact of key 18, the tip contacts of plug 13 and jack 20, and the upper alternate contact of relay 10 24 to ground. Supervisory lamp 17 of the link circuit D is lighted over a circuit extending from battery through the contact of relay 14, the normal contact of listening key 15, and the lower contact of relay 16, and the lamp 17 to ground. Relay 16 is locked over 20 a circuit extending from battery through the contact of relay 14, the normal contact of relay 15, the upper contact of relay 16 and the right-hand winding of relay 16, to ground. The illumination of lamp 17 serves as a disconnect signal to the operator at office W who may thereupon remove the plug 13 from the jack 20, causing the release of relay 16, 30 to extinguish the lamp 17 and of relays 14 and 21, the release of the latter relay also causing the release of relay 28. The opening of the middle alternate contact of relay 21 introduces a break in the circuit holding relay 1, but the latter relay does not release 35 at this time due to the closed conditions of the middle alternate contacts of relays 41 and 61. The removal of the plug 13 of the link circuit D from the jack 120 at office Z 40 also causes the release of relays 14, 121 and 128, and although the opening of the middle contact of relay 121 introduces a break in the circuit of relay 101, the latter relay is maintained operated due to the continued closure 45 of the middle alternate contacts of relays 141 and 161.

Operator at office Z transmits disconnect signal to the operator at office W over line circuit B.

Upon the completion of the conversation, 50 the operator at office Z actuates ringing key 18, causing the operation of relay 145 over a circuit extending from the source of alternating current through the lower alternate contact of ringing key 18, the ring contacts of plug 13 and jack 140, the lower normal contact of relay 144, one winding of the repeating coil, the winding of relay 145 and the condenser 151 shunted by the condenser 152, the upper normal contact of relay 144, 55 the tip contacts of jack 140 and plug 13, and the upper alternate contact of key 18 to ground. The closure of the left-hand contact of relay 145 short-circuits the winding

of the repeating coil thereby effectually preventing the induction of the ringing current into the out-going section of the phantom line circuit B. The closure of the right-hand contact of relay 145 causes the operation of relay 150 over a circuit extending from battery through the winding of relay 150, the left-hand normal contact of relay 149, the right-hand alternate contact of relay 148, and the right-hand contact of relay 145 to ground. Relay 149 operates over a circuit extending from battery through the alternate contact of relay 150, the winding of relay 149 and the left-hand normal contact of relay 130 to ground. The opening of the left-hand normal contact of relay 149 releases relay 150 and the subsequent opening of the alternate contact of the latter relay causes the release of relay 149. However, during the interval that relay 149 is operated a circuit is completed from the negative terminal of the 120 volt source of current through the contact of relay 147, the right-hand alternate contact of relay 149, the right-hand normal contact of relay 129, the upper winding bridged around relay 134, the simplex conductors of the line circuit A leading from office Z to office Y, the winding of relay 86, the lower winding bridged around relay 86, and the normal contacts of relays 82 and 83 in series, to ground. The direction of current flow through this circuit is such that relay 86 closes its upper contact to cause the operation of relay 84 over an obvious circuit. The closure of the right-hand alternate contact of relay 84 produces no material effect upon the system while the closure of the left-hand alternate contact thereof completes, during the continuation of the impulse, a circuit extending from the negative terminal of the 120 volt source of current through the left-hand alternate contact of relay 84, the upper bridged winding around relay 81, the simplex conductors of line circuit A extending from office Y to office X, the winding of relay 5, the simplex conductors of the line circuit A extending from office X to office W the winding of relay 34, 100 the lower winding bridged therearound, the left-hand normal contact of relay 29 and the left-hand normal contact of relay 49, to ground. The direction of current flowing through the last-mentioned circuit causes relay 5 to close its left-hand contact and relay 34 to close its upper contact. The operation of relay 5 does not change the conditions existing at office X inasmuch as relay 7 remains locked independent of relay 5. The closure of the upper contact of relay 34, 105 causes the operation of relay 44 over a circuit extending from battery through the winding of relay 44, the left-hand alternate contact of relay 41 and the upper contact of relay 34 to ground. Therefore dur-

ing the continuation of the impulse a circuit is completed extending from the source of alternating current through the lower alternate contact of relay 44, the ring contacts of jack 40 and plug 13, the lower normal contact of key 18, the left-hand winding of supervisory relay 16, the condenser 19, the upper normal contact of key 18, tip contacts of plug 13 and jack 40, and the upper alternate contact of relay 44, to ground. Relay 16, in responding thereto, causes the lighting of lamp 17 over a circuit extending from battery through the contact of relay 14, the normal contact of key 15, the lower contact of relay 16, and the lamp 17 to ground. As in the previous case, relay 16 is locked over a circuit extending from battery through the contact of relay 14, the normal contact of key 15, the upper contact of relay 16, and the right-hand winding of such relay to ground. In response to the illumination of the lamp 17, the operator at office W removes the plug 13 from the jack 40 to release relays 16, 14, 41 and 48 at office W, and by opening the middle alternate contact of relay 41, introduces another break in the circuit controlling relay 1, which, however, still remains energized due to the ground at the middle alternate contact of relay 61. In a similar manner the removal of the plug 13 from the jack 140 at office Z causes the release of relays 14, 141 and 148 and introduces another break in the circuit controlling relay 101.

Operator at office Z transmits a disconnect signal to the operator at office W over the line circuit C.

Upon the completion of the conversation over line circuit C the operator at office Z actuates ringing key 18 of the link circuit D associated therewith to complete a circuit extending from the source of alternating current through the lower alternate contact of key 18, the ring contacts of plug 13 and jack 160, the lower normal contact of relay 164, one winding of the repeating coil, the winding of relay 165, and the condenser 171 shunted around condenser 172, the upper normal contact of relay 164, the tip contacts of jack 160 and plug 13 and the upper alternate contact of key 18 to ground. Relay 165 responds to such current and the closure of the left-hand contact thereof short-circuits the winding of the repeating coil to effectually prevent the inducing of the alternate current into the outgoing section of the line circuit. The closure of the right-hand contact of relay 165 causes the operation of relay 170 over a circuit extending from battery through the winding of relay 170, the left-hand normal contact of relay 169, the right-hand alternate contact of relay 168, and the right-hand contact of relay 165 to ground. Relay 169 then operates over a circuit extending from battery through the right-hand alternate contact of relay 170, and the winding of relay 169, to ground. The opening of the left-hand normal contact of relay 169 releases relay 170 which in turn opens the operating circuit of relay 169. However, during the operation of relay 169, a circuit is completed from the positive terminal of the 120 volt source of current through the normal contact of relay 167, the right-hand alternate contact of relay 169, the upper winding bridged around relay 174, the simplex conductors of line circuit C extending from office Z to office Y, the winding of relay 96 and the upper winding bridged therearound, and the normal contacts of relays 92 and 93 in series to ground. The direction of current flowing through this circuit is such that relay 93 closes its lower contact to cause the operation of relay 95 over an obvious circuit. The closure of the left-hand contact of relay 95 establishes a circuit during the continuation of the impulse which extends from the positive terminal to the 120 volt source of current through the left-hand alternate contact of relay 95, the left-hand normal contact of relay 94, the lower winding bridged around the winding of relay 91, the simplex conductors of line circuit C extending from office Y to office X, the winding of relay 6, the simplex conductors of line circuit C extending from office X to office W, winding of relay 74, the lower winding bridged therearound, the left-hand normal contact of relay 69 and the right-hand alternate contact of relay 1 to ground. Although the current flowing through this circuit causes relay 6 to close its left-hand contact no effect is produced upon the system since relay 7 is locked independently of relay 6. However, the current flowing through the winding of relay 74 causes it to close its lower contact thereby causing the operation of relay 64, over a circuit extending from battery through the winding of relay 64, the left-hand alternate contact of relay 61, and the lower contact of relay 74 to ground. Therefore, during the continuation of the impulse a circuit is established from the source of alternating current through the lower alternate contact of relay 64, the ring contacts of jack 60 and plug 13, the lower normal contact of key 18, the left-hand winding of relay 16, the condenser 19, the upper normal contact of key 18, the tip contacts of plug 13 and jack 60 and the upper alternate contact of relay 64 to ground. Relay 16 causes the lighting of supervisory lamp 17 as in the previous cases and is locked over a circuit similar to that described in the other instances. In response to the illumination of the lamp 17, the operator at office W removes plug 13 from jack 60, causing the re-

lease of relays 16, 14, 61 and 68, as in connection with the other line circuits, while the removal of the plug 13 from the jack 160 also causes the release of relays 14, 161 and 168, at office Z in a manner similar to that previously described. In addition to these operations, however, the opening of the middle alternate contact of relay 61 introduces a final break in the circuit of relay 1, causing such relay to release. The release of relay 1 causes the release of relay 2 but due to the fact that the latter-mentioned relay is slow in releasing, a temporary circuit is established extending from the negative terminal of the 120 volt source of current through the alternate contact of relay 2, the normal contact of relay 1, the left-hand normal contact of relay 69, the upper bridged winding around relay 74, the simplex conductors of line circuit C, extending from office W to office X, the winding of relay 6, the simplex conductors of line circuit C extending from office X to office Y, the winding of relay 91 and the upper winding bridged therearound, the normal contacts of relays 94 and 95 in series to ground. The direction of current flowing through this circuit is such as to cause relay 6 to close its right-hand contact and relay 91 to close its upper contact. The closure of the right-hand contacts of relay 6 causes the operation of relay 8 over an obvious circuit and the opening of the contact thereof releases relay 7. The opening of the middle and right-hand contacts of relay 7 disables the filament battery supply circuits for repeaters RA1 and RC1 at office X. The closure of the upper contact of relay 91 operates relay 92 over an obvious circuit. The opening of the left-hand normal contact of relay 92 releases relay 90 and the opening of the middle and right-hand contacts thereof disables the filament battery supply circuit of repeaters RA2 and RC2 at office Y. Although the closure of the right-hand alternate contact of relay 92 completes a circuit extending from the negative terminal of the 120 volt source of current through the right-hand alternate contact of relay 92, the lower bridged winding around relay 96, the simplex conductors of line circuit C, extending from office Y to office Z, the winding of relay 174, the lower winding bridged therearound, the left-hand normal contact of relay 169, the left-hand normal contact of relay 101, and the normal contact of relay 102 to ground, no effect is produced upon the system due to the direction of flow of the current.

60 What is claimed is:

1. In a system comprising a plurality of lines and a repeater, the method of operating and disabling the repeater which comprises transmitting an impulse over any one of the lines, causing the impulse to render the re-

peater operative, transmitting an impulse current over only one of the lines and causing the second-named impulse to disable the repeater.

2. In a telephone system, a plurality of 70 transmission lines, repeaters associated with certain of said lines, signaling circuits connected to certain of said lines, means controlled over said signaling circuits for rendering said repeaters effective, and means controlled over only one of said signaling circuits for disabling said repeaters.

3. In a telephone system, a plurality of 80 transmission lines, repeaters associated with certain of said lines, signaling circuits connected to certain of said lines, means controlled over said signaling circuits for rendering said repeaters effective, and means common to said transmission lines and effective to transmit an impulse over only one 85 of said signaling circuits for disabling said repeaters.

4. In a telephone system, a plurality of 90 transmission lines, signaling circuits connected to certain of said lines, repeaters associated with certain of said lines, means for transmitting signaling impulses over said 95 signaling circuits when calls are initiated on said lines and means for transmitting an impulse over only one of said signaling circuits for controlling said repeaters.

5. In a telephone system, a plurality of 100 transmission lines, signaling circuits connected to certain of said lines, repeaters associated with certain of said lines, means for transmitting signaling impulses over said 105 signaling circuits when calls are initiated on said lines, and means common to said lines for transmitting an impulse over only one of said signaling circuits for rendering said 110 repeaters ineffective.

6. In a telephone system, a plurality of 110 transmission lines, repeaters associated with certain of said lines, means for producing impulses to be transmitted over certain of said lines when a call is initiated, a signaling circuit common to certain of said lines and connected to one of the lines over which impulses are to be transmitted, a second signaling circuit associated with another of said lines, means responsive to impulses transmitted over either of said signaling circuits for rendering said repeaters effective and responsive to an impulse over only one of said 115 circuits for disabling said repeaters, and means responsive to certain of said impulses for indicating the particular line taken for the initiation of a call.

7. In a telephone system, physical and 125 phantom lines, repeaters associated with the physical lines, means for producing impulses to be transmitted over said physical lines when calls are initiated on said lines, a signaling circuit common to certain of said lines and connected to one of the phy- 130

sical lines, a second signaling circuit associated with the other physical line, means responsive to impulses transmitted over either of said signaling circuits for rendering said repeaters effective and responsive to an impulse over only one of said circuits for disabling said repeaters, and means responsive to certain of said impulses for indicating the particular line taken for the initiation of a call.

5. The method which comprises transmit-

ting impulses over a number of lines, rendering effective a plurality of repeaters in response to one of said impulses, translating said impulses into signals, transmitting an ¹⁵ impulse over only one of said lines, and disabling said repeaters in response to the second-named impulse.

In witness whereof, I hereunto subscribe my name this 26th day of December A. D., ²⁰ 1919.

LOUIS A. MORTIMER.
